UNITED STATES PATENT OFFICE.

IDA RIEGER, OF NEW YORK, N. Y., ASSIGNOR TO ALPHA EMBROIDERY CO., OF WEST NEW YORK, NEW JERSEY, A CORPORATION OF NEW JERSEY.

DESIGN FOR LACE.

42,590.

Specification for Design.

Patented June 4, 1912.

Application filed April 3, 1912. Serial No. 688,311. Term of patent 3½ years.

To all whom it may concern:

Be it known that I, IDA RIEGER, a citizen of Switzerland, and a resident of the borough of Manhattan, city, county, and State of New York, have invented a new, original, and ornamental Design for Lace, of which the following is a specification, reference being had to the accompanying drawing, forming part thereof.

The figure is a plan view of a portion of the lace, showing my new design.

I claim:

The ornamental design for lace, as shown.

IDA RIEGER.

Witnesses:

JOS. H. SULZBACHER,
FELIX MEYER.
